DESCRIPTION

U.S. PATENT DOCUMENTS

This application is related to the following applications: U.S. patent application No. 14/694,872, filed Apr. 23, 2015, U.S. Design patent application No. 29/488,838, filed Apr. 23, 2014, and U.S. Design patent application No. 29/488,839, filed Apr. 23, 2014, each of which is hereby incorporated by reference in its entirety.

FIG. 1 is a perspective view of an embodiment of our new design of a base with wheels for a temporary display rack.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is a bottom view of another embodiment of the design of FIG. 1.

The broken lines in the Figures are for illustrative purposes only and form no part of the claimed design.
